UNITED STATES PATENT OFFICE.

JOSEPH R. B. NORFOLK, OF CHICAGO, ILLINOIS.

ARTIFICIAL LEG.

1,352,682.

Specification of Letters Patent. Patented Sept. 14, 1920.

Application filed June 9, 1919. Serial No. 302,658.

To all whom it may concern:

Be it known that I, JOSEPH R. B. NORFOLK, a citizen of the United States, residing at Chicago, in the county of Cook and State of Illinois, have invented certain new and useful Improvements in Artificial Legs, of which the following is a specification.

My invention relates to artificial legs, and has more particular reference to knee-joints and suspender constructions therefor.

The principal objects of these improvements are, to provide leg mechanism the action of which may be so controlled by the wearer that the artificial leg will have a substantially natural movement; further, to provide a construction in which the artificial leg may be flexed with substantially natural movements under the weight of the wearer's body, this feature enabling the wearer to walk up and down stairs in the natural way, or to rise naturally from a sitting posture, and to perform other natural movements by strains exerted on the artificial leg. It is a further object to provide an improved structure for holding the artificial leg in all operative positions by a substantially uniform downward pull upon the wearer's shoulder, thus avoiding the well-known unequal or "drawing" strains which cause the suspender to move upon the shoulder, sometimes forward and sometimes rearward, attended by notable discomfort.

A further object is to provide a structure whereby the movements of the lower leg may be controlled by a shoulder independently of the shoulder which supports the leg, thus creating an advantageous division of labor for the shoulders and giving the wearer greater freedom and capacity for action than where the same shoulder or shoulders perform both operations. It is also an object to provide an improved form of adjustable stop for limiting the forward movement of the lower leg relative to the upper leg. A further object is to provide an improved leg-support-and-control mechanism which may readily be applied to substantially all forms of artificial legs and various forms of leg braces now in use. A still further object is to provide means for adjusting the hinge pin for the upper and lower leg members with respect to its bearing so as to maintain a tight joint there.

Other objects and advantages will appear hereinafter.

In the accompanying drawings, which form a part of this specification, I have illustrated these improvements in what I now consider their most advantageous form as applied to an artificial leg. In these drawings Figure 1 shows the several parts in assembled relation, in an outside view; Fig. 2 is an enlarged substantially medial fore-and-aft, vertical section through the knee-joint portions of the leg; Fig. 3 is a substantially medial, vertical section through the same parts at right angles to the view of Fig. 2; Fig. 4 is a side view with knee portions of the upper leg broken away to show interior parts in side view.

The upper leg 10 is a hollow structure formed to receive the stump of the wearer's thigh, and may be made according to any well-known construction, it usually being of light-weight wood. It has a knee portion at 11 which is rounded there substantially on the arc of a circle having its center at the hinge pin 12. This hinge pin 12 in itself is of well known construction. It is tubular and is threaded interiorly at its ends to receive the cap screws 13. To provide a strong seat for the hinge pin 12 I insert the transverse piece 14 made of hard wood. This piece 14 acts as a bearing for the pin 12 and the weight of the wearer's body is normally transmitted to the pin through this bearing member.

The lower leg 15 is similarly made of light weight material, such as wood, is also a hollow structure, and is formed substantially to interfit at its top with the knee portion 11 of the upper leg member, but with sufficient clearance to prevent frictional contact, as shown in Fig. 2.

The upper and lower leg members are secured operatively together through the medium of a unitary structure which is rigidly secured to the lower leg and upon the hinge pin 12. This unitary member is preferably formed of several parts, chiefly for purposes of assembling and disassembling the knee joint structure. These parts comprise first a pair of normally vertical metallic side members 16, secured respectively as by bolts or screws 17 at opposite middle upper side portions of the lower leg, this member 16 having an enlargement provided with an opening at its upper end adapting it to fit upon the end of the hinge pin 12, this element 16 thereby constituting

the main support for the lower leg member. Next in order is the cross bar member 18, which is also apertured to fit upon the end of the hinge pin 12, and next I provide 5 the yoke member 19 which is secured, preferably by machine screws 20, to the cross bar 18 and by a similar screw 21 to the supporting bar 16. After these screws 20 and 10 21 are inserted and drawn tight they are preferably battered a little at their inner ends to prevent accidental retraction, and in this connection it is pointed out that the unitary structure consisting of the parts 16, 15 18 and 19 may be assembled before the supporting bar 16 is secured to the lower leg. The cap screws 13 in the ends of the pin 12 serve to hold this unitary structure upon the pin 12.

It will be noted that one end of the hinge 20 pin 12 is exteriorly threaded at 23. The supporting member 16 on that side is interiorly threaded to screw upon this threaded portion 23. By thus connecting the hinge pin to one of the supports 16 the 25 assembling of the device is facilitated.

The arms of the yoke member 19 act as struts and ties, making rigid and strong the connection between the cross member 18 and supporting element 16 so that the lower 30 leg member may be controlled through strains exerted upon this cross member 18. For exerting such controlling strains the cross member 18 is extended forward on each side to provide a pulling lever 25, and 35 this lever 25 is preferably in the form of a one-piece yoke of flat steel, the arms of which are the cross bars 18. This yoke 25 has a normally horizontal slot at 26 adapted to receive the end of the flexible pulling 40 element 27, which is preferably a piece of woven tape about an inch and a half wide, this tape being secured in strong pulling relation to the yoke 25, as by stitching the overlapping end portions together.

45 The pull member 27 is maintained in proper relation to the upper leg by a metallic confining strap 30 secured there. Thence the pull strap 27 passes upward and is formed loop-shaped at 27^a, this loop 27^a 50 normally encompassing the shoulder of the wearer on the same side as is the artificial leg. Thus in the device illustrated the loop 27^a passes over the wearer's left shoulder and the artificial leg is on the left side of 55 his body. When the leg is in its operative position the loop 27^a fits snugly upon the wearer's shoulder so that when the artificial leg is flexed at the knee joint a lifting-up movement of the left shoulder will pull 60 upon the strap 27, communicating its power to the lever 25 and thence to the supporting element 16, thus straightening the leg, as shown in Fig. 1. In these movements of alternately flexing and straightening the leg 65 66 the hinge pin 12 turns upon the bearing

block 14, the hinge pin being rigid with the pull lever 25 and with the parts 16 and 19 connected therewith.

The forward movement of the lower leg is limited by an improved stop device which 70 comprises a bifurcated head 32 transversely bored to receive the adjustable bearing block 33, which is crescent shaped in side view, as seen in Fig. 2, and fits snugly upon the hinge pin 12. This bearing block 33 is preferably of bronze while the rest of the stop member is of iron or steel. The block 33 has two studs 34 which project loosely through holes in the head 32 and retain the block 33 in place and prevent its rocking 80 in the head 32. Two set screws 35 projecting through the head 32 impinge upon the middle portion of the bearing block 33 and maintain the bearing block tightly upon the hinge pin 12, this feature taking up wear 85 and preventing the objectionable and annoying looseness and clicking sound due to loose parts in a device of this kind.

Extending from the head 32 of the stop member is the bar 37 which is directed first 90 toward the rear of the leg and thence downward into the upper part of the lower leg, its lower end having a notch at 38 through which passes the adjusting screw shaft 39. A U-shaped nut 40 encompasses the end of 95 the rod 37, and this nut is threaded upon the shaft 39 and acts as a carrier for the end of the rod 37. The shaft 39 has a head 42 adapted to be turned by a screw driver, while a washer 43 held in place by a screw 44 prevents, in connection with the head 42, any longitudinal movement of the shaft 39. Pieces of metal 45 and 46 are inserted at 10 these places in the lower leg for purposes of better wear. The stop bar 37 travels 10 in a normally vertical slot 46 in the lower middle rear of the upper leg whenever relative movement of the lower leg occurs. This slot terminates at 47, at which place a cushion element, such as a piece of leather, is 11 inserted to engage the stop 37. It will now be seen that by turning the screw shaft 39 one way or the other the stop 37 will engage the leather or the like at 47 with the lower leg perfectly straight up and down with 11 respect to the upper leg, or bent slightly forward or rearward, according to the preference of the user, it being pointed out that some users prefer to have the line of direction of the wearer when standing upon the 12 artificial leg slightly forward of the hinge pin, others preferring this line of direction to pass through the dead center, while others prefer a slight bend forward at the knee when the stop device becomes effective. 12

The entire artificial leg is maintained in operative position by a flexible strap or holding member 50, which is substantially U-shaped and passes from the artificial leg upward and over the shoulder on the oppo- 13

site side of the body to the one having the artificial leg, the strap 50 passing over the right shoulder in the device shown. Tie straps 51, 51^a hold the controlling strap 27, 27^a and the holding strap 50 together and prevent either from slipping off of the wearer's shoulder. The strap 50 passes down in front of the artificial leg through the retaining yoke 30 and passes into the interior of the upper leg through an opening accommodating the roller 52, while at the rear the strap 50 passes through a similar opening and in engagement with the roller 53.

Upon the hinge pin 12 I provide a cross bar device 55 in the nature of a walking beam, the same fitting upon the shaft 12 for rocking movement thereon.

This device 55 is an equalizer of the swingletree type. Its ends are turned over to form an eye at 56 adapted to accommodate the link 57, a screw 58 at each end holding the link in the eye 56. The ends of the holding strap 50 are secured to the links 57 respectively, and when so secured and the device is in operative position the length of the holding strap 50 is such that the same fits snugly upon the wearer's shoulder and maintains the upper leg 10 in its desired relation to the wearer's stump.

The function of the equalizer bar 55 is to take up slack in the holding strap 50, either front or back as the case may be, and pay out slack in the strap 50 at its other end. Thus when the wearer seats himself he naturally bends his body over in front. This causes slack in the front extension of the strap 50 and at the same time the curvature of the wearer's back increases the distance from the shoulder to the artificial leg behind and without some equalizing means the wearer would experience a tight drawing of the strap 50 upon his shoulder and back and this would be sufficient to cause a slippage of the strap 50 upon his shoulder and back, which would be both annoying and hurtful.

With this equalizer bar connected to the strap 50 as illustrated the pull upon the rear extension of the strap 50 draws upward the rear arm of the equalizer 55, while the other end is freely permitted to move downward because of the slack in the front extension of the strap 50. No movement of the strap 50 therefore occurs on the wearer's shoulder, but the artificial leg is at all times held in its desired relation to the stump.

It is not new to provide in artificial legs an equalizer of the type described, as witness the U. S. Patent to Frees, No. 401,426, of April 16, 1889. My improved equalizer construction is highly advantageous over the one there shown for various reasons, among which I may mention that no addi-

tional pivot over the one for the knee joint is required, thus taking advantage of the presence of an unusually strong hinge pin while avoiding the additional weight and expense of an additional bearing pin for the equalizer; also in having a unitary mechanism for supporting the leg and for controlling the lower leg—a mechanism which can be readily installed not only in new but also in old leg structures; furthermore the equalizer in my present device is maintained against lateral movement by its being in the bifurcation of the head 32, well shown in Fig. 3, so that the desired action is always to be had. It is further advantageous in that an adjustment of the hinge pin 12 to overcome looseness, as hereinafter pointed out, makes at the same time the desired adjustment for the leg holding means.

The further feature of improvement referred to next hereinabove is in the provision of adjusting means for maintaining the hinge pin 12 in tight-fitting operative relation to its bearing 23 to overcome wear. These means comprise the two-part or yoke-like head member 60, its two parts 60 being bored transversely to fit loosely upon the hinge pin 12. The yoke 60 carries the central stud 61 which passes through the transverse metallic support 62, and the nut 63 draws the yoke 60 upward. When wear occurs in the bearing block 14 so that there is looseness and play in the joint a slight turning of the nut 63 restores the desired fit.

I claim:

1. The combination of an upper leg member, a lower leg member, a hinge-pin pivotally connecting said members, an equalizing bar pivotally mounted intermediate its ends on said hinge-pin, and a flexible suspender having one of its ends connected to one end of said equalizing bar and its other end connected to the other end of the equalizing bar, the suspender having a length enabling it to pass over the wearer's shoulder and hold the artificial leg in place.

2. The combination of an upper leg member, having a knee portion, a lower leg member, a hinge-pin pivotally connecting said members, a yoke extending forward outside the leg in front at the knee and having its ends carried by the ends of the hinge-pin, a connection securing the lower leg member to the hinge-pin at each end portion of the hinge-pin, means for holding the yoke and said connection rigidly together whereby a movement of the yoke moves the lower leg members relative to the upper leg member at the hinge-pin, and a flexible pull member secured to the yoke in front and forming a loop for the wearer's shoulder.

3. The combination of an upper leg member having a knee portion, a lower leg member, hinge means for pivotally connecting said members, a yoke extending forward

100

105

110

115

120

125

130

from the hinge means and passing around the knee in front, means for connecting said yoke rigidly to the lower leg member, and a flexible pull member connected to the yoke 5 in front and having a loop for the wearer's shoulder.

4. The combination of an upper leg member having a knee portion, a lower leg member pivotally connected to the upper leg 10 member, a pull lever extending forward from the pivotal connection of said members, means for holding said pull lever in rigid relation to the lower leg member, and means under the control of the wearer 15 for pulling upon said pull member.

5. The combination of an upper leg member having a knee portion, a lower leg member pivotally connected to the upper leg member, an equalizing bar pivotally mounted intermediate its ends near the knee portion, a flexible support adapted to pass substantially U-shaped over one of the wearer's shoulders and having its two ends connected to respective ends of said equalizing bar, a 25 leg-control lever rigidly secured to the lower leg and extending forward to a point normally in front of the hinge connection between the leg members, and a flexible pull member secured to said pull lever and having a loop for the other shoulder of the 30 wearer.

6. The combination of an upper leg mem-

ber, a lower leg member, hinge means connecting the two members, a stop pivotally mounted on said hinge means and extending 35 into the lower leg member, a threaded shaft extending from front to back in the lower leg member, said shaft being threaded into said stop member whereby turning said shaft moves said stop member forward or 40 backward on its pivotal connection, and stop means on the lower leg adapted to come into contact with said stop member when the lower leg is moved forward on its hinge connection.

7. The combination of an upper leg member, a lower leg member, a hinge-pin connecting the two members pivotally, the upper leg member having a bearing for the hinge-pin, and adjustable means 50 for limiting the relative movement of the lower leg including a bar mounted on the hinge-pin and extending into the lower leg member, a threaded member mounted to rotate in the lower leg member, said arm being 55 mounted on said threaded member to move relatively when said threaded member is rotated, and a stop on the upper leg member adapted to contact said bar, the arrangement being such that by rotating said threaded 60 member the forward movement of the lower leg is variously limited.

JOSEPH R. B. NORFOLK.
